(57) **CLAIM**

The ornamental design for a footbed for a shoe, as shown and described.

DESCRIPTION

FIG. 1 is a front view of a footbed for a shoe.

FIG. 2 is a rear view of the footbed of FIG. 1.

FIG. 3 is an inner-side view of the footbed of FIG. 1.

FIG. 4 is an outer-side view of the footbed of FIG. 1.

FIG. 5 is a top view of the footbed of FIG. 1.

FIG. 6 is a bottom view of the footbed of FIG. 1.

FIG. 7 is a top, front and outer-side isometric view of the footbed of FIG. 1.

FIG. 8 is a bottom, rear and inner-side isometric view of the footbed of FIG. 1.

FIG. 9 is a cross-sectional view of the footbed taken along line 9-9 of FIG. 5.

FIG. 10 is a cross-sectional view of the footbed taken along line 10-10 of FIG. 5.

FIG. 11 is a cross-sectional view of the footbed taken along line 11-11 of FIG. 5.

FIG. 12 is a cross-sectional view of the footbed taken along line 12-12 of FIG. 5.

FIG. 13 is a cross-sectional view of the footbed taken along line 13-13 of FIG. 5.

FIG. 14 is a cross-sectional view of the footbed taken along line 14-14 of FIG. 5.

FIG. 15 is a front view of a footbed for a shoe.

FIG. 16 is a rear view of the footbed of FIG. 15.

FIG. 17 is an inner-side view of the footbed of FIG. 15.

(Continued)

FIG. 18 is an outer-side view of the footbed of FIG. 15.
 FIG. 19 is a top view of the footbed of FIG. 15.
 FIG. 20 is a bottom view of the footbed of FIG. 15.
 FIG. 21 is a top, front and outer-side isometric view of the footbed of FIG. 15.
 FIG. 22 is a bottom, rear and inner-side isometric view of the footbed of FIG. 15.
 FIG. 23 is a cross-sectional view of the footbed taken along line 23-23 of FIG. 19.
 FIG. 24 is a cross-sectional view of the footbed taken along line 24-24 of FIG. 19.
 FIG. 25 is a cross-sectional view of the footbed taken along line 25-25 of FIG. 19.
 FIG. 26 is a cross-sectional view of the footbed taken along line 26-26 of FIG. 19.
 FIG. 27 is a cross-sectional view of the footbed taken along line 27-27 of FIG. 19.
 FIG. 28 is a cross-sectional view of the footbed taken along line 28-28 of FIG. 19.
 FIG. 29 is a top, front and outer-side isometric view of a footbed for a shoe.
 FIG. 30 is a front view of the footbed of FIG. 29.
 FIG. 31 is a rear view of the footbed of FIG. 29.
 FIG. 32 is an outer-side view of the footbed of FIG. 29.
 FIG. 33 is an inner-side view of the footbed of FIG. 29.
 FIG. 34 is a top view of the footbed of FIG. 29.
 FIG. 35 is a bottom view of the footbed of FIG. 29.
 FIG. 36 is a bottom, rear and outer-side isometric view of the footbed of FIG. 29.
 FIG. 37 is a cross-sectional view of the footbed taken along line 37-37 of FIG. 34.
 FIG. 38 is a cross-sectional view of the footbed taken along line 38-38 of FIG. 34.
 FIG. 39 is a cross-sectional view of the footbed taken along line 39-39 of FIG. 34.
 FIG. 40 is a cross-sectional view of the footbed taken along line 40-40 of FIG. 34.
 FIG. 41 is a cross-sectional view of the footbed taken along line 41-41 of FIG. 34.
 FIG. 42 is a front view of a footbed for a shoe.
 FIG. 43 is a rear view of the footbed of FIG. 42.
 FIG. 44 is a top view of the footbed of FIG. 42.
 FIG. 45 is a bottom view of the footbed of FIG. 42.
 FIG. 46 is an inner-side view of the footbed of FIG. 42.
 FIG. 47 is an outer-side view of the footbed of FIG. 42.
 FIG. 48 is a top, front and outer-side isometric view of the footbed of FIG. 42.
 FIG. 49 is a top, rear and inner-side isometric view of the footbed of FIG. 42.
 FIG. 50 is a cross-sectional view of the footbed taken along line 50-50 of FIG. 44.
 FIG. 51 is a cross-sectional view of the footbed taken along line 51-51 of FIG. 44.
 FIG. 52 is a cross-sectional view of the footbed taken along line 52-52 of FIG. 44.
 FIG. 53 is a cross-sectional view of the footbed taken along line 53-53 of FIG. 44.
 FIG. 54 is a cross-sectional view of the footbed taken along line 54-54 of FIG. 44.
 FIG. 55 is a cross-sectional view of the footbed taken along line 55-55 of FIG. 44.
 FIG. 56 is a front view of a footbed for a shoe.

FIG. 57 is a rear view of the footbed of FIG. 56.
 FIG. 58 is an inner-side view of the footbed of FIG. 56.
 FIG. 59 is an outer-side view of the footbed of FIG. 56.
 FIG. 60 is a top view of the footbed of FIG. 56.
 FIG. 61 is a bottom view of the footbed of FIG. 56.
 FIG. 62 is a top, front and inner-side isometric view of the footbed of FIG. 56.
 FIG. 63 is a bottom, rear and outer-side isometric view of the footbed of FIG. 56.
 FIG. 64 is a cross-sectional view of the footbed taken along line 64-64 of FIG. 60.
 FIG. 65 is a cross-sectional view of the footbed taken along line 65-65 of FIG. 60.
 FIG. 66 is a cross-sectional view of the footbed taken along line 66-66 of FIG. 60.
 FIG. 67 is a cross-sectional view of the footbed taken along line 67-67 of FIG. 60.
 FIG. 68 is a cross-sectional view of the footbed taken along line 68-68 of FIG. 60; and,
 FIG. 69 is a cross-sectional view of the footbed taken along line 69-69 of FIG. 60.
